LIMITED, OF SHEFFIELD, ENGLAND.

STEAM HYDRAULIC INTENSIFIER.

1,383,399.

Specification of Letters Patent.

Patented July 5, 1921.

Application filed February 26, 1919. Serial No. 279,395.

To all whom it may concern:

Be it known that I, THOMAS WILTON HAND, a subject of the King of Great Britain, residing at Sheffield, England, have invented new and useful Improvements in Steam Hydraulic Intensifiers, of which the following is a specification.

When a hydraulic forging or like press, actuated by a steam hydraulic intensifier, is required to work not with long and comparatively slow pressing strokes but with a succession of short and rapid strokes performed against the constant pressure of a cushion of live steam then maintained beneath the pistons in the presshead lifting-cylinders, it is necessary for the realization of the greatest economy in steam consumption that the preliminary or idle portion of each such short pressing stroke should be kept as small as possible by carefully adjusting, from time to time, what may be termed the starting-position of the presshead and forging tool to suit the gradually diminishing depth of the work, so that the tool, in the course of a series of such strokes, may not be called upon to descend idly through a gradually increasing distance before it actually encounters the work. This adjustment, which involves admitting a further supply of water from the air-vessel to the hydraulic main pressure pipe so as to increase the effective length of the hydraulic column, is in practice seldom made, and consequently a considerable proportion of each working stroke of the intensifier is taken up in producing the idle portion of the stroke of the press, with the result that, as the intensifier steam cylinder requires to be charged during its entire working stroke with steam at a pressure sufficient to overcome the resistance encountered when the tool comes into actual contact with the work, great waste of steam is liable to occur. The disadvantage becomes the more apparent in view of the fact that the intensifier steam piston is allowed to rise to that intermediate point in its stroke whereat its further ascent becomes effective for producing pressure upon the work, short reversals of movement being effected about this intermediate point for the purpose of producing the rapid finishing strokes of the presshead and tool, and the steam piston being seldom allowed to fall to its bottom position, so that

the entire space beneath the steam piston has to be alternately opened to exhaust and re-charged with steam notwithstanding the relative shortness of the effective portion of each upward stroke.

The primary object of the present invention is to minimize this wasteful expenditure of steam, notwithstanding any neglect which may occur in adjusting the starting-position of the presshead and tool relatively to the work; for which purpose, according to the invention, each time the intensifier steam piston performs a downward or return movement, the lower end of the steam cylinder is not opened to the exhaust as heretofore, but the opposite ends of the intensifier steam cylinder are put into communication with one another in a closed circuit so that, the steam which produced the previous upward or working stroke of the intensifier being now allowed to expand into the space above the piston until equilibrium of pressures is produced on its opposite sides, the piston and attached parts become free to descend by gravity. At other times the upper end of the intensifier steam cylinder may be in communication with the exhaust, to which the expanded steam is discharged during the performance by the steam piston of each upward or working stroke.

The means employed for carrying out the invention comprise an additional or secondary exhaust valve interposed between the main exhaust pipe and a passage connecting the delivery side of the primary exhaust valve with the upper end of the steam cylinder of the intensifier, and means for causing this secondary exhaust valve to be opened and closed concurrently with the opening and closing of the steam inlet valve.

As a result of the method of operation above described, when the intensifier steam piston begins each downward, or return movement, there will always exist beneath this piston steam at a reduced pressure dependent upon the position whence the piston descends, so that if the presshead has not been properly adjusted (in the manner previously set forth) with a view to economical working, the volume of steam beneath the piston will be saved because, in order to produce the next upward or working stroke of the intensifier, it will only be necessary to admit so much addi-

tional steam beneath the piston as is necessary to restore the pressure to the amount required.

In addition to the saving of steam thus effected, a further advantage is obtained owing to the fact that, as the time required for establishing equilibrium of pressures on opposite sides of the intensifier steam piston is much less than that required for reducing the steam beneath this piston to atmospheric pressure (as with arrangements at present in use) the intensifier steam piston and attached parts will descend more promptly than heretofore and will permit of the presshead being lifted to raise the tool from the work with correspondingly greater promptitude by the action of the cushion of live steam maintained beneath the pistons in the presshead lifting-cylinders, while the intensifier steam piston itself will have a greater tendency to remain near the lower end of its stroke, which is the position best adapted for insuring economical working.

In a practical embodiment of the invention as applied to a steam hydraulic intensifier constructed in other respects substantially as described in the specification of the application for Letters Patent filed on 19th January, 1918, Serial No. 212,550, the intensifier steam cylinder is provided, in addition to the usual upwardly-opening steam inlet and exhaust valves adapted to open in alternation with one another, with a second upwardly-opening exhaust valve placed beneath and in axial alinement with the steam inlet valve and attached to the inlet valve spindle so as to be opened and closed concurrently with the opening and closing of the inlet valve itself; the primary exhaust valve serving only to control communication between the lower end of the intensifier steam cylinder and a branch which leads from the upper end of the intensifier steam cylinder to the space above the secondary exhaust valve, while this latter exhaust valve controls communication between said branch and the main exhaust pipe.

In the accompanying drawings illustrating a convenient form of such an arrangement as applied to a hydraulic forging press constructed substantially as described in the specification accompanying my application for Letters Patent filed 4th November, 1918, Serial No. 261,132, Figure 1 is a diagrammatic side elevation of the steam hydraulic intensifier, whereof the steam and hydraulic cylinders are shown in axial section, as are also the valves for controlling the steam connections appertaining to the steam cylinder of the intensifier and the lifting cylinders of the press. Fig. 2 is a similar side elevation of the hydraulic press operated by the steam hydraulic intensifier illustrated in Fig. 1, the hydraulic cylinder and the two

lifting-cylinders of the press being shown in axial section.

The ram 11 of the press (Fig. 2) reciprocates vertically in the hydraulic cylinder 12 and performs its working strokes in the downward direction; the ram 11 carrying at its lower end the presshead 13, which is fitted to slide on vertical pillars 14 connecting the top plate or entablature 15, whereon the hydraulic cylinder 12 and the steam lifting-cylinders 16 are mounted, with the base-plate 17 which supports the anvil 18. The work 19 is forged upon the anvil by the tool 20 carried by the presshead, the upward or return strokes of the tool and press head being effected by the admission of steam to the lifting cylinders 16 beneath their pistons 21 which are connected to the presshead 13 by vertical piston-rods 22 fitted to slide through stuffing-boxes 23 in the lower ends of the cylinders 16.

The hydraulic main pressure pipe 24 connects the upper end of the hydraulic cylinder 12 of the press with the lower end of the hydraulic cylinder 25 of the intensifier (Fig. 1) and the hydraulic "working" valve 26. This valve 26, which is interposed in the pipe 24 and is adapted to be operated by the handing-lever which controls both the press and the intensifier, serves to govern the connection between the hydraulic main 24 and the usual air vessel 28 by way of the hydraulic low pressure pipe 29 in the well-known manner of such apparatus.

The ram 30 of the intensifier reciprocates vertically in the hydraulic cylinder 25 and performs its working stroke in the upward direction; the ram 30 carrying at its lower end a crosshead 31 which is coupled by vertical side-rods 32 to the piston 33 of the steam cylinder 34 of the intensifier. The hydraulic cylinder 25 of the intensifier is placed beneath the steam cylinder 34 and is fixed at 35 to the lower member of a stool or open frame 36 the upper member 37 of which is shown as constituting the bottom of the steam cylinder 34; the side rods 32, which are guided at 38 in the lower member of the stool, passing through stuffing-boxes 39 in the bottom 37 of the steam cylinder. 115

The steam inlet-and-exhaust port 40 of the intensifier steam cylinder 34 is connected on the one hand with the main steam supply pipe 41 by way of the steam inlet valve 42 and on the other hand, by way of the primary exhaust valve 44, with a passage 43 which is permanently connected, by a pipe 43^a, with the space above the piston 33 in the cylinder 34, and which can be put in communication with the main exhaust pipe 45 by way of the secondary exhaust valve 46. All these valves 42, 44 and 48 are shown as of the double-beat "drop" type, and open upwardly; the passage which connects the delivery side of the inlet valve 42 130

with the port 40 passing through the casing of the primary exhaust valve 44 above the latter valve itself. The secondary exhaust valve 46 is placed beneath and in axial alignment with the inlet valve 42 and is actuated by the same spindle which actuates the inlet valve; while all three valves 42, 44 and 46 are adapted for being controlled on the one hand manually by means of a single 10 handing-lever 47, and on the other hand automatically by means of hunting-gear adapted to cause the supply of steam to the cylinder 34 to be cut off, during each working stroke of the intensifier, at a point corresponding to the angular position wherein 15 for the time being the handing-lever is held.

For the purpose of effecting the manual control of the valves, the handing-lever 47, which is fulcrumed at a fixed point 47^a, has 20 an arm 48 coupled by an upright rod 49 to the longer arm of what may be termed the "main" lever 50 of the valve-actuating mechanism, this "main" lever 50, which is substantially horizontal, being fulcrumed at 25 a fixed point 51 at a level considerably above the valves. 52 is a "floating" lever which is connected by one end to the shorter arm of the main lever 50 and by the opposite end to an intermediate point in the upper section 30 of an upright link 71 formed in two sections which are coupled together by a pin-and-slot connection 71^a, the lower end of the lower section of this link being connected to the spindle 57 of the primary exhaust 35 valve 44; and 53 is a substantially horizontal "rocking" lever which is fulcrumed at a fixed point 54 beneath the level of the main lever 50 and floating lever 52; this rocking lever being coupled at one end to the spindle 55 of the steam inlet valve 42 and secondary exhaust valve 46 by a pin-and-slot connection 56, at the opposite end to an intermediate point in the lower section of the link 71 by a pin-and-slot connection 59, and, 40 at a point between said connection 59 and the fulcrum 54, to an intermediate point in the floating lever 52 by means of an up-right link 58.

The hunting-gear for effecting the automatic control of the valves is actuated by 45 an upright, upwardly-tapering cam-bar 60 fixed at 61 to, and extending upward from, the crosshead 31 and having one edge 62 inclined to the direction of motion of the 50 bar while the opposite edge, which is parallel to said direction, is guided by contact with a stationary roller 63. Against the inclined edge 62 of this cam-bar, bears a roller 64 carried by one limb of a three-armed 55 lever 65 which is fulcrumed at a fixed point 66, contact between the roller and cam-bar being insured by a counterweight 67 suspended from a second limb of the lever 65. A third limb of the same lever is coupled 60 by an upright rod 68 to one arm of what

may be termed the "secondary" lever 69 (as distinguished from the "main" lever 50) of the valve-actuating mechanism; this "secondary" lever 69, which is fulcrumed at a fixed point 70 above the level of the floating 70 lever 52, having its other arm connected to the upper end of the link 71 and thus to that end of the floating lever 52 which is remote from the main lever 50.

In operation, each time the steam piston 75 33 and hydraulic ram 30 of the intensifier are required to perform an upward or working stroke, the handing-lever 47 is moved, from the mid or neutral position shown, toward the right so as to open the steam inlet 80 valve 42 and admit live steam beneath the piston 33 in the intensifier steam cylinder 34; this movement causing the secondary exhaust valve 46 to open as well (while the primary exhaust valve 44 remains closed) 85 so as to put the upper end of the cylinder 34 into direct communication with the main exhaust pipe 45 by way of the pipe 43^a and passage 43. When the piston 33 and ram 30 are subsequently required to perform a 90 downward or return stroke, the handing-lever 47 is moved toward the left so as to close the steam inlet valve 42 and open the primary exhaust valve 44; this movement causing the secondary exhaust valve 46 to 95 close as well, so that the steam beneath the piston 33 cannot pass to the main exhaust pipe 45 but is free to expand by way of the passage 43 and pipe 43^a into the space above the piston. This expansion of the 100 steam thus takes place in a closed circuit, while the piston 33, hydraulic ram 30, and attached parts descend by gravity. Next time the steam inlet valve 42 is opened to bring about an upward stroke of the piston 105 33 and ram 30, the concurrent opening of the secondary exhaust valve 46 permits the steam from above the piston 33 to be discharged into the main exhaust pipe 45.

It is to be observed that when, during an 110 upward or working stroke of the steam piston 33 and hydraulic ram 30 of the intensifier, said piston and ram reach a level corresponding to the angular position in which for the time being the handing-lever 47 is 115 held, the action of the hunting-gear will cause the steam inlet valve 42 to close so that the upward movement will be arrested and the piston and ram will be supported by the steam beneath the piston until, as the result 120 of a subsequent movement of the handing-lever toward the left of its neutral position, the primary exhaust valve 44 is opened so as to permit of the expansion of the steam, from beneath the piston 33 into the space 125 above the same as already stated.

From the foregoing, it will be apparent that the sequence of steps in the different operations of my improved hydraulic intensifier will be as follows:—Upon moving 130

lever 47 to the right (to cause a working stroke of the piston 33) rod 49 will be moved upward by arm 48, thereby moving the longer arm of main lever 50 upward, and 5 depressing the shorter arm of said lever and with it the end of floating lever 52 that is connected thereto. Through the link 58 which connects the floating lever 52 with the longer arm of the rocking lever 53, said arm 10 will be depressed, thereby elevating the shorter arm of lever 53, thereby raising the common spindle of valves 42 and 46 and thus opening both of said valves, valve 44 meanwhile not being moved from its closed position. Live steam will thereupon be admitted through port 40 to the lower end of cylinder 34, below piston 33, and exhaust steam will pass from the upper end of the cylinder through conduit 43^a and into exhaust pipe 15 45. When piston 33 has been moved upward a distance dependent upon the extent to which lever 47 has been moved to the right, the vertical arm of three-armed lever 65 will be moved to the left, due to engagement of roller 64 thereon with the inclined surface 62 of cam-bar 60, depressing the arm of secondary lever 69 which is connected by rod 68 with a horizontal arm of three-armed lever 65, and thereby elevating the end of 20 floating lever 52 which is connected with the upper section of link 71. This will elevate the longer arm of rocking lever 53, thereby closing valves 42 and 46. Pin 59 on the longer arm of rocking lever 53 will mean- 25 while move upward idly in the slot in the lower section of link 71 and the upper section of said link will telescope on the lower section thereof, so that valve 44 will remain closed. All three of the valves 42, 46 and 44 30 as thus closed, and the piston 33 and ram 30 are left supported by the steam beneath the piston. To cause the piston to perform a downward or return stroke, hand-lever 47 is moved to the left of its neutral position, 35 which movement, while leaving valves 42 and 46 in the closed position, opens valve 44, whereby the live steam beneath the piston enters the exhaust steam contained in the passage between the rear of the piston and the now closed exhaust pipe 45, since port 40 has now an open connection with conduit 43, 43^a, (and hence with the upper end of cylinder 34), thus permitting equalization of 40 the steam pressure on the two sides of the piston. The piston and ram 30 will now move downward by gravity until their descent is halted by moving hand-lever 47 to its neutral position, thereby closing the valve 44 and holding all three of the valves 42, 46 45 and 44 in closed position, leaving the piston and the ram supported by the exhaust steam below the piston. As is well known, the piston in a device of this character when in use is seldom, if ever, allowed to proceed to 50 the extreme end of the cylinder on its return

stroke, but is stopped at an intermediate point, so as to minimize its distance of travel toward the work. Upon the closing of valve 44 the weight and momentum of the piston and the ram and the parts connected therewith will cause them to continue their descent until the exhaust steam below the piston becomes compressed sufficiently to prevent their further downward movement, this compression being accompanied by expansion of the exhaust steam above the piston and in conduit 43^a. Upon again moving hand-lever 47 to the right of its neutral position, to cause another working stroke of the piston, the live steam admitted by the opening of valve 42 will meet the compressed exhaust steam below the piston and in port 40, thereby reducing the amount of live steam required for the working stroke, and only expanded exhaust steam from above the piston and in conduit 43^a must be expelled through exhaust pipe 45 as the working stroke of the piston takes place thereby lessening the opposition offered by said exhaust steam to the working stroke of the piston. 55 The entire manipulations required of the operator are of the simplest nature and the apparatus is automatic in action, requiring only that the workman shall watch the work-piece on the anvil and throw the lever 47 when the tool 20 has delivered its blow and when, ascending, it has cleared the work-piece.

In the example illustrated, the steam connections to the lifting-cylinders 16 are controlled by a vertically-working piston-valve 72 (hereinafter referred to as the lifting-cylinder valve), which is actuated by the hand-lever 47. The casing of the valve 72 has four sets of ports at different levels; the 100 lowest set of ports 73 being connected by a branch 74 to the main steam supply pipe 41 while the highest set of ports 75 are connected by a pipe 76 to the main steam exhaust pipe 45. Of the two intermediate sets 105 of ports, the upper set 77 are connected by a pipe 78 and branches 79 and 80 to the upper end of the respective lifting-cylinders 16; while the lower set 81 are connected by a pipe 82 and branches 83 and 84 to the lower 110 end of the respective lifting-cylinders. The valve-piston has two cylindrical faces 85 and 86 separated by a waist-portion 87 of reduced diameter; the lengths of the faces 85, 86, and their distance apart, being such that, 115 so long as the valve-piston rests, as shown, in its normal or lowest position, the ports 73 and 81 are connected together, and the ports 75 and 77 are also connected together but at the same time separated from the ports 73 and 81, so that on the one hand steam is admitted from the main steam supply pipe 41 (by way of the branch 74, ports 73 and 81, pipe 82, and branch pipes 83 and 84) to the 120 lower ends of the lifting-cylinders 16, and 125 130

on the other hand communication is opened from the upper ends of the cylinders 16 (by way of the branch pipes 79 and 80, pipe 78, ports 77 and 75, and branch pipe 76) to the main steam exhaust pipe 45; whereas, when the valve-piston occupies an intermediate position, both the steam ports 73 and exhaust ports 75 of the valve are closed, and communication is established between the lower and upper ends of the lifting-cylinders 16 (by way of the branch pipes 83 and 84, pipe 82, ports 81 and 77, pipe 78, and branch pipes 79 and 80) between the lower and upper ends of the lifting-cylinders 16.

15 The valve-piston 85, 86, 87 is attached to a weighted spindle 88 which, passing out through a stuffing-box at the end of the valve-casing, is connected, through a combined telescopic joint and automatically-acting detent-and-trip mechanism of known construction indicated at 90, with a rod 89 permanently attached to the "main" lever 50.

So long as the handing-lever 47, "main" lever 50, and piston-valve 85, 86, 87 occupy substantially the position shown, the telescopic joint permits free movement of the rod 89 relatively to the valve-spindle 88 in either direction within predetermined limits, 30 but when the handing-lever 47 is angularly displaced toward the left so as to depress the lever 50 and rod 89 beyond a certain limit, the valve-spindle 88 becomes automatically engaged with the rod 89 and hence, 35 when the handing-lever is returned toward the right, the valve-piston 85, 86, 87 is raised along with the lever 50 until, on the valve-piston passing upward beyond the intermediate position already referred to, the 40 valve spindle 88 becomes automatically disengaged from the rod 89 so that the valve-piston is free to fall back to its lowest position.

From the foregoing it will be seen, first, 45 that so long as the valve-piston 85, 86, 87 is in its normal or lowest position, a cushion of high-pressure steam will be maintained in the lifting-cylinders 16 beneath the pistons 21 which will accordingly (assuming other 50 conditions to be favorable) tend to rise and lift the presshead 13 and ram 11, owing to the absence of steam pressure above the pistons 21 in consequence of the upper ends of the cylinders 16 being open to the exhaust pipe; secondly, that when the valve-piston is raised from the lowest to the intermediate position, high-pressure steam will no longer be able to gain access to the cylinders 16 beneath the pistons 21, while the 55 steam already beneath these pistons will be allowed to pass from the lower to the upper side of the pistons and will expand until, equilibrium of pressures being established on the opposite sides of the lifting-pistons, 60 the presshead 13 and ram 11 (if previously 65

raised) will be free to descend under gravity; and thirdly, that the valve-piston, when further raised to the level at which it is released from the lever 50, will automatically return to the lowest position, thus restoring 70 the cushion of high-pressure steam beneath the lifting-pistons 21 while allowing the expanded steam above said piston to become exhausted so that (other conditions being favorable) the presshead 13 and ram 11 will 75 again tend to rise.

The working-valve 26, the construction and operation of which are fully described in the specification the application for Patent No. 212,550, already referred to, is 80 controlled (as previously stated) by the handing-lever 47; for which purpose the arm 48 of the handing-lever is coupled by a rod 91 to a lever 92 which acts upon the spindle of the working-valve. This valve, 85 which normally cuts off communication between the air vessel 28 and the hydraulic main pressure pipe 24, is adapted, when open, to permit water to flow from the pipe 24 to the air vessel or vice versa according 90 to circumstances the opening of the valve being produced by means of the handing-lever 47 when it is required to reduce the quantity of water in the pipe 24 and cylinders 11 and 25, but being effected automatically when 95 it is required to fill up the vacuum created in the pipe 24 and cylinders 11 and 25 by the idle descent of the rams 11 and 30 or either of them.

In the foregoing description, the elastic 100 motive fluid operating in the intensifier and in the lifting-cylinders of the hydraulic press is for the sake of convenience referred to as "steam," but it will be evident that other elastic motive fluid (such as compressed air for example) may be used; and hence it is to be understood that both throughout the description and in the appended claims the term "steam" is to be interpreted as including any kind of elastic 105 motive fluid.

Having now particularly described and ascertained the nature of my said invention and in what manner the same is to be performed, I declare that what I claim is:— 115

1. A steam hydraulic intensifier comprising a steam cylinder, a piston movable therein, hydraulic means connected with said piston, an inlet for live steam to said cylinder, an exhaust outlet therefrom, a steam connection between opposite ends of said cylinder, whereby the steam pressure upon opposite sides of said piston is equalized during the return stroke thereof, and means for compressing exhaust steam on the working side of said piston during completion of the return stroke thereof, whereby such compressed exhaust steam is met by the live steam admitted to the cylinder for the next working stroke of the piston. 120 125 130

2. A steam hydraulic intensifier comprising a steam cylinder, a piston movable therein, hydraulic means connected with said piston, an inlet for live steam to said cylinder, 5 an exhaust outlet therefrom, a steam connection between opposite ends of said cylinder, whereby the steam pressure upon opposite sides of said piston is equalized during the return stroke thereof, and means for expanding the steam on the idle side of said piston during completion of the return stroke thereof, and thereby lessening the opposition offered by said steam to the next working stroke of the piston. 10
- 15 3. A steam hydraulic intensifier comprising a steam cylinder, a piston movable therein, hydraulic means connected with said piston, an inlet for live steam to said cylinder, an exhaust outlet therefrom, a steam connection between opposite ends of said cylinder, whereby the steam pressure upon opposite sides of said piston is equalized during the return stroke thereof, and means for compressing exhaust steam on the working side of said piston during completion of the return stroke thereof while expanding the steam on the idle side of said piston during the completion of the return stroke, whereby such compressed exhaust steam is 20 met by the live steam admitted to the cylinder for the next working stroke while the opposition offered by the exhaust steam to said next working stroke is lessened. 25
4. In a steam hydraulic intensifier, the combination of a steam cylinder, a piston movable therein, hydraulic means connected with said piston, an inlet for admission of live steam to said cylinder to effect movement of said piston on the working stroke, a steam connection between the opposite ends of said cylinder, means for closing said connection prior to initiating the working stroke of said piston and for opening it during the return stroke, whereby during such 40 return stroke exhaust steam has access to the idle side of said piston, and steam at a pressure at least equal to said equalized pressure is interposed between the piston and the live steam admitted to effect the next 45 succeeding working stroke and coöperates therewith, and an exhaust for the spent steam from said cylinder open during the working stroke of the piston. 50
5. In a steam hydraulic intensifier the combination of a steam cylinder, a piston movable therein, hydraulic means connected with said piston, a conduit connecting the cylinder on opposite sides of said piston, an exhaust connection communicating with said 55 conduit, a steam inlet to one end of the cylinder, valves to control the steam inlet, the conduit and the exhaust, and means for controlling said valves to close the valve in the conduit prior to the opening of the 60 steam inlet and exhaust valves and to open 65 the conduit valve subsequent to the closing of the steam inlet and exhaust valves, whereby the full volume of steam employed during the power stroke is retained in the system represented by the two sides of the piston and the conduit between them during the return stroke, and the maximum quantity of steam is conserved on the power side of the piston at the time when live steam is again admitted to said side thereof. 70
6. The combination of an upwardly-acting steam hydraulic intensifier including an upright steam cylinder, a piston movable vertically therein, an inlet for the power fluid at the lower part of said cylinder to elevate the piston on the working stroke, a conduit connecting the opposite ends of said cylinder means for closing said conduit during the working stroke of the piston and for opening it during its return stroke whereby during said return stroke steam pressure upon opposite sides of said piston is equalized, permitting the return stroke of the piston to be influenced by gravity, means for establishing a cushion of steam at a pressure at least 80 equal to said equalized pressure below the piston in position to coöperate with the live steam in effecting the next succeeding working stroke, an exhaust connected with said conduit, valves controlling said conduit, said inlet and said exhaust and means for operating said valves in coördination with each other. 85
7. The combination of a hydraulic press, an upwardly-acting steam hydraulic intensifier structurally independent of said press and connected therewith, said intensifier including an upright steam cylinder and a piston vertically movable therein, an inlet for the power fluid at the lower part of said cylinder to elevate the piston on the working stroke, a valve in said inlet, a conduit connecting the opposite ends of said cylinder, means for closing said conduit during the working stroke of the piston and for 90 opening it during its return stroke, whereby during said return stroke steam pressure upon opposite sides of said piston is equalized, permitting the return stroke of the piston to be influenced by gravity, means for maintaining a cushion of steam at not less than said equalized pressure between the steam inlet valve and the lower surface of the piston until the next succeeding working stroke, a steam inlet connected with said conduit, an exhaust connected with said conduit, an exhaust valve controlling said exhaust, an additional exhaust valve controlling said conduit and means for operating the additional exhaust valve concurrently with the 95 operation of the steam inlet valve. 100
8. In a steam intensifier the combination of a steam cylinder, a piston movable therein, hydraulic means, connection between the said hydraulic means and said piston, said 110
- 115
- 120
- 125
- 130

connection operating to reduce the pressure area of the piston on that side thereof receiving the working force of the steam, a conduit connecting the cylinder on opposite 5 sides of said piston, means for closing said conduit during the working stroke of the piston and for opening it during the return stroke thereof whereby during said return stroke steam pressure upon opposite sides 10 of said piston is equalized, a steam inlet

whereby live steam is admitted to one end of the cylinder and added to steam at not less than said equalized pressure to effect the working of the piston and a vent connected with said conduit and arranged to 15 open during the working stroke whereby the steam previously conducted to said opposite side of the piston is exhausted during said working stroke.

THOMAS WILTON HAND.
